UNITED STATES PATENT OFFICE.

CHARLES L. JENNETTE, OF NORLINA, NORTH CAROLINA.

HANGER FOR CAR DOORS.

Application filed August 20, 1919. Serial No. 318,708.

To all whom it may concern:

Be it known that I, CHARLES L. JENNETTE, a citizen of the United States, residing at Norlina, in the county of Warren and State 5 of North Carolina, have invented a new and useful Hanger for Car Doors, of which the following is a specification.

This invention relates to sliding door construction, and more particularly to sliding 10 doors used in connection with freight cars, or the like.

The primary object of the invention is to provide a sliding door capable of easy operation, and one which will be securely supported 15 against displacement.

A further object of the invention is to provide a door which will be supported on rollers disposed adjacent the lower edge of the door, thereby relieving the upper portion 20 of the door, and bracket thereof, of undue strain, which is ordinarily directed thereto, by the freight car.

A further object of the invention is to provide brackets having means for engaging the 25 inner surface of the supporting tracks, thereby securing the door against lateral displacement.

With the foregoing and other objects in view which will appear as the description 30 proceeds, the invention resides in the combination and arrangement of parts and in the details of construction hereinafter described and claimed, it being understood that changes in the precise embodiment of the invention herein disclosed, may be made within 35 the scope of what is claimed without departing from the spirit of the invention.

Referring to the drawings:—

Figure 1 illustrates a side elevational view 40 of a portion of a car having a door constructed in accordance with the present invention applied thereto.

Figure 2 illustrates a longitudinal sectional view taken on line 2—2 of Figure 1.

Figure 3 is a perspective view of one of the 45 upper brackets, used in connection with the present invention.

Figure 4 illustrates a perspective view of one of the lower, or roller supporting bracket.

Having reference to the drawings in detail, reference character 5 designates a portion 50 of a freight car, provided with the usual door opening 6. The track sections include the upper horizontal casing member 7, and lower horizontal member 8, each of which is

supported in spaced relation with the side of the car 5, by means of the bolts 9.

The closure 10, is made up of a plurality of vertically extending boards, and is of a size to completely close the opening, when 60 the door is in its closed position. As shown, the lower portion of the door, or closure 10, is provided with cut-out portions 11, which cut-out portions are of a size to receive the body portion which includes the laterally extending arms 12, of the bracket members 13, each bracket member including upwardly extending arms 14, apertured as at 15, to receive suitable securing means, the arms 14, 65 extending below the arms 12, and terminating in an upwardly, and inwardly extending hook portion 16.

Each of these arms 12, is provided with an elongated slot 17, to provide a support for the roller 18, which is also supported on a 70 pintle 19, positioned in the openings 20 and 21, formed in the arms.

From the foregoing, it will be seen that the weight of the car door, is removed, from the securing bolts 21, the arms 12 supporting 80 the weight of the door, which arms transfer the weight to the rollers 18, and permit of easy movement of the door, along the track sections.

In order to prevent lateral displacement of 85 the door, 9, with relation to the car proper, the upper brackets 22, are secured to the upper portion of the door 9.

Each of the brackets 22, includes the body portion 23, which has downwardly extending arms 24, apertured to receive the securing bolts 25, to permit the same to be rigidly connected to the door 9.

An upwardly extending hook member 26, is formed integral with the body portion 23, 95 and is provided with a downwardly extending flange 27, cooperating with the upwardly extending flange 28, provided on the laterally extending arm 29, for engaging the upper track section 7, thereby preventing lateral 100 displacement of the upper portion of the door, with relation to the track sections.

The latch member is indicated at 30 and cooperates with the keeper 31 secured to the door frame so that the door will be held in its 105 locked position.

Having thus described the invention, what is claimed is:—

In combination with a sliding closure and track sections supported adjacent to the 110

lower edge thereof, a hanger comprising a pair of spaced arms, the lower ends of said arms merging into an integral hook portion formed with a groove to fit over the track section, a body portion formed integral with the arms and extending laterally therefrom, the body portion having its ends extended beyond the arms to provide a bracket for the door, said body portion having a cut out portion to accommodate a roller, and a pintle

extending through the body portion to support a roller.

In testimony that I claim the foregoing as my own, I have hereto affixed my signature in the presence of two witnesses.

CHARLES L. JENNETTE.
